FIG. 1

FIG. 2

INVENTOR
JOHN N. MORTIMER
BY *Ray Shulie, Ray*
ATTORNEYS -

UNITED STATES PATENT OFFICE.

JOHN N. MORTIMER, OF LAKEWOOD, OHIO, ASSIGNOR TO THE CENTRAL BRASS MANUFACTURING COMPANY, OF CLEVELAND, OHIO, A CORPORATION OF OHIO.

DESIGN FOR A PLUMBING-FIXTURE.

50,151.

Specification for Design.

Patented Jan. 9, 1917.

Application filed October 26, 1916. Serial No. 127,958. Term of patent 7 years.

To all whom it may concern:

Be it known that I, JOHN N. MORTIMER, a citizen of the United States, and resident of Lakewood, county of Cuyahoga, and State of Ohio, have invented a new, original, and ornamental Design for Plumbing-Fixtures, of which the following is a specification, reference being had to the accompanying drawing, forming part thereof.

In said annexed drawing: Figure 1 is a front elevation, and Fig. 2 is a side elevation

of a plumbing fixture, showing my new design.

I claim:

The ornamental design for a plumbing fixture, as shown.

Signed by me, this 23 day of October, 1916.

JOHN N. MORTIMER.

Attested by—

HERMAN L. LISS,
W. O. PEPPER.
